TOP ROLL

William C. Wright, Hickory, N. C.

Application July 27, 1950, Serial No. 176,141

2 Claims. (Cl. 19—142)

1

This invention relates to textile machinery of the type which employs drafting or drawing rolls and more especially to top rollers used with such machinery.

Many attempts have been made to provide satisfactory top rolls for spinning frames and the like and none of the top rolls heretofore in use have proven satisfactory since it has been relatively difficult to remove any accumulation of yarns from the cots of the top rolls which may be wrapped therearound. Also, as is well known, the central portions of most top rolls are fixedly engaged by a weighted member or saddle and, upon continuous rotation of the top rolls over periods of relatively long durations, the friction between the weighted member and the top rolls results in grooves or ridges being worn in the central portion of the top roll. This would retard rotation of the top rolls.

It is, therefore, an object of this invention to provide a top roll assembly comprising a shaft on which a pair of spaced rolls are fixedly mounted, the remote ends of the two rolls being spaced apart from the adjacent ends of the shaft and the space between the spaced rolls being provided with a sleeve or roller neck which is rotatably mounted on the medial portion of the shaft thus permitting the shaft to rotate relative to the sleeve and the rolls to rotate with the shaft.

It is another object of this invention to provide a top roll of the type described wherein a pair of anti-friction or ball bearings are provided within opposed ends of the centrally disposed sleeve or roller neck, the inner races of the bearings being fixed on the shaft, as by a pressed fit, and the outer races thereof being fixed in the opposed ends of the sleeve to thus permit the shaft to rotate freely within the sleeve and thus permitting the rolls on opposed end portions of the shaft to rotate freely with the shaft and independently of the sleeve, the sleeve or roller neck being adapted to support the usual weight member or saddle associated with the top rolls for urging the top rolls into engagement with the corresponding bottom rolls.

Some of the objects of the invention having been stated, other objects will appear as the description proceeds when taken in connection with the accompanying drawings in which—

Figure 1 is a vertical-sectional view through a set of top and bottom rolls of a spinning frame or the like and showing the same in association with the usual weight member or saddle and one of the roll stands;

Figure 2 is a top plan view of the improved top

2

roll showing the same in association with fragmentary portions of the bearings for supporting the top roll and the saddle;

Figure 3 is a longitudinal vertical-sectional view through the top roll shown in Figure 2 and showing the manner in which the saddle engages the medial portion of the top roll assembly and also showing the positioning means for the top roll assembly which is a usual part of a spinning frame or the like for holding the top roll in alignment with the corresponding bottom roll;

Figure 4 is an enlarged vertical sectional view taken substantially along the line 4—4 in Figure 3;

Figure 5 is an enlarged vertical sectional view taken substantially along the line 5—5 in Figure 3.

Referring more specifically to the drawings, the numeral 10 indicates a roll stand board, only a portion of which is shown in cross-section in Figure 1, on which a plurality of roll stands 11 are mounted, there being only one of these roll stands shown in Figure 1. The roll stands 11 have suitable bearing portions therein in which are mounted front, middle and back bottom corrugated rolls 12, 13 and 14, respectively. The roll stands 11 are usually spaced a substantial distance apart from each other and have fixedly secured therebetween a conventional rod 15 on which are pivotally mounted a plurality of top roll supporting members, only two of which are shown in Figures 1, 2 and 3 indicated at 17. Only fragmentary portions of the top roll supporting members 17 are shown in Figure 2 and these are provided with suitable cavities 20 on opposed sides thereof in which the ends of arbors of top rolls, to be presently described, are mounted for rotation.

Referring to Figure 1, there will be observed three top rolls, a middle top roll 21, a front top roll 21a and a rear top roll 21b, all of which may be identical and which coincide with the respective bottom rolls 13, 12 and 14. Since the top rolls 21, 21a and 21b may all be identical, only the middle top roll 21 is shown in detail in Figures 2 to 5, inclusive.

Each of the top rolls is urged into engagement with the coinciding bottom rolls, in this instance, by means of a first saddle 23 and a second saddle 24, the saddle 23 engaging the roller necks, to be presently described, of the middle and back top rolls 21 and 21b and the second saddle 24 engaging the upper surface of an identical roller neck of the front roll 21a. The rolls 21, 21a and 21b are provided to hold a sliver S downwardly in contact with the upper surfaces of the respective bottom rolls, 13, 12 and 14 as the sliver or slivers

S travel from between the back rolls 21b and 14 to the front rolls 12 and 21a. The first saddle 23 is slotted, said slot being defined by the dotted lines 25 and 26 in Figure 1, and this slot is loosely penetrated by a link member 27 which projects upwardly and curves forwardly and is pivotally connected, as at 30, to the front or second saddle 24.

The link member 27 extends downwardly from the saddles 23 and 24, between the back and middle top and bottom rolls and its lower end is slidably penetrated by a weight lever 32 having a top hook portion disposed within an eye bolt 34 threadably secured in the roll stand board 10. The weight lever 32 extends rearwardly from the lower end of the link 27 and has a suitable weight 35 on the rear end thereof for applying pressure to the saddles 23 and 24 and to the top rolls 21, 21a and 21b to press the same toward the respective bottom rolls 13, 12 and 14.

Improved top roll

Referring to Figures 2, 3, 4 and 5, the improved top roll 21 is shown in detail and it will be observed in Figures 2 and 3 that the top roll 21 is shown in association with the top roll support member 17 and the saddles 23 and 24 which are shown schematically.

The improved top roll comprises an arbor or shaft 40, opposed ends of which are adapted to have rotational movement in the corresponding notches 20 of the top roll support members 17 and on the opposed end portions of which spaced bosses 41 and 42 are fixedly secured, as by headless set screws 43. Both of the bosses 41 and 42 are identical and of tubular construction and the headless set screws 43 are tightened against the arbor or shaft 40 so as to tightly secure the bosses 41 and 42 thereon against relative movement with the shaft 40 and so that the outer ends of the set screws 43 will not extend beyond the outer periphery of the corresponding bosses 41 and 42. These bosses 41 and 42 are spaced substantially apart from each other and a roller neck 44 having enlarged end portions 45 and 46, is disposed between the proximate ends of the bosses 41 and 42. The enlarged end portions 45 and 46 define a peripheral groove 48 extending around the center of the roller neck and adapted to receive the saddles or any suitable weight member.

The roller neck 44 may be rotatably mounted on the medial portion of the arbor 40 and may slidably and rotatably engage the proximate surfaces of the bosses 41 and 42 if desired. However, it is preferred that the opposed ends of the roller neck 44 each be recessed, as at 47, and for reception of the outer race 50a of a ball or anti-friction bearing 50, and the outer race 50a of the ball bearing 50 preferably being secured in the recessed ends 47 of the roller neck 44 as by a pressed fit, and the inner race 50b of the ball bearing 50 being secured to the arbor 40 as by a pressed fit. The inner race 50b and the arbor 40 rotate while the roller neck 44 and outer race 50a remain stationary.

In order to insure that the proximate ends of the bosses 41 and 42 do not engage the remote or opposed ends of the roller neck 44, but to insure that they will be positioned in closely spaced relation to the opposed ends of the roller neck 44, the inner or proximate ends of each of the bosses 41 and 42 have an annular recess 52 therein and the depth of the recesses 47 in the proximate ends of the roller neck 44 is such that the outer

race 50a of each ball bearing 50 will extend slightly beyond the respective outer end of the roller neck 44 and this portion of the outer race 50a of the ball bearing 50 which is not confined in the recess 47 projects into the annular recess 52 in the proximate end of the corresponding boss 41 or 42. The annular recess 52 defines an inner annular projection 53 which is adapted to engage the outer edge of the inner race 50b of the ball bearing 50 and, since the inner race 50b of the ball bearing 50 is preferably pressed onto the shaft or arbor 40 and the corresponding boss 41 or 42 turns in fixed relation to the shaft or arbor 40, it is thus seen that the inner race 50b of the ball bearing 50 and the annular projection 53 will be in fixed relation to each other and will permit relative movement between the roller neck 44 and the corresponding bosses 41 and 42 and the inner race 50b of the ball bearing 50 will prevent the bosses 41 and 42 from sliding on the shaft 40 to where their inner ends will engage the proximate ends of the roller neck 44.

It is thus seen that the roller neck 44 may support the corresponding saddles 23 and 24 or any suitable weight member and may, in turn, through the medium of the anti-friction bearing 50, transmit the weight to the bosses 41 and 42 to urge the same toward the bottom rolls.

After the roller neck 44, the ball or anti-friction bearing 50 and the bosses 41 and 42 are successively or progressively mounted on the arbor 40 so that the opposed ends of the arbor 40 extend beyond the remote ends of the bosses 41 and 42, suitable cots 54 and 55 may be adhesively or otherwise secured on the respective bosses 41 and 42. These cots 54 and 55 may be of any desired material such as rubber, leather, fabric and the like, and it is preferred that the peripheral surfaces of the bosses 41 and 42 be roughened or grooved to insure that the corresponding respective cots 54 and 55 may be fixedly secured on the respective bosses 41 and 42.

Since it is only necessary that a few thousandth of an inch clearance be provided between the outer ends of the roller neck 44 and the inner or proximate ends of the bosses 41 and 42, it is thus seen that it will be impossible for any lint or other foreign matter to accumulate therebetween and interfere with the function of the anti-friction bearings 50. It is preferred that these anti-friction bearings be of the type having seals 56 on opposed sides thereof to obviate the necessity of lubricating these bearings.

An important feature of this type of top roll is that it may easily be employed in lieu of other types of rolls on roving frames, spinning frames, twisters and the like, since this type of structure is such that the exterior dimensions of the various parts of the top roll may be substantially the same as those which may have been replaced thereby. It is well known by those familiar with the art that the sliver S will, at times, become severed or broken as it passes between the top and bottom rolls thus resulting in the end of the sliver S being wound about the adjacent top roll and, also, in many instances, the fibers in the sliver may become separated and some of the fibers will wind around the adjacent top roll and this requires that the top roll be removed from the machine and grasped by an operator as the accumulation of lint or fibers thereon are twisted off the cot. In other types of rolls wherein the roller neck has been an integral part of the arbor and the bosses have been rotatably mounted on the arbor, it has been difficult to prevent rotation

of one of the bosses relative to the other while removing the accumulation of lint and fibers therefrom and this is overcome by the present invention.

It is evident that, in removing the accumulations of fibers from the present top roll by grasping either of the bosses 44 or 42 or the cots thereon, this will prevent rotation of the other of the bosses and will thus simplify the operation of removing the accumulation of fibers from the other of the cots resulting in a saving in the time required to do so.

It is thus seen that I have provided an improved top roll for drafting machines comprising an arbor having a pair of bosses affixed thereto and a roller neck rotatably mounted thereon between the bosses and which will permit the bosses and the arbor to rotate while the roller neck remains stationary thus avoiding wear on the roller neck of the top roll which has heretofore been the result of saddles or weight members resting thereon and also permitting the rolls to rotate freely without the resistance which has heretofore been caused by the weight means usually associated with drafting machines. This will result in a more efficient drafting operation than has heretofore been possible and will also lengthen the life of the top roll considerably above that of top rolls heretofore in use.

In the drawings and specification, there has been set forth a preferred embodiment of the invention and although specific terms are employed, they are used in a generic and descriptive sense only and not for purposes of limitation, the scope of the invention being defined in the claims.

I claim:

1. An improved top roll for fiber processing machines such as spinning frames, roving frames, twisters and the like, comprising an arbor, a pair of axially spaced bosses fixedly mounted on said arbor, a roller neck disposed between said bosses and encircling said arbor, opposed ends of the roller neck having an annular recess therein, a pair of anti-friction bearings having inner and outer races, the outer races of said bearings being secured in said annular re-

cesses in opposed ends of the roller neck and the inner races being secured to said arbor, each of the bosses having an annular projection on its end adjacent the roller neck, said annular projection being adapted to engage the outer edge of the corresponding inner race of the anti-friction bearing to thus insure that the proximate ends of the axially spaced bosses will be disposed in closely spaced relation to the adjacent ends of the roller neck and whereby the bosses and the arbor may rotate freely relative to the roller neck and vice versa.

2. An improved top roll for fiber processing machines such as spinning frames, roving frames, twisters and the like, comprising an arbor, a pair of spaced bosses fixedly mounted on said arbor, a roller neck disposed between said bosses and encircling said arbor, opposed ends of the roller neck having a recess therein, a pair of anti-friction bearings having inner and outer races, the outer races of said bearings being secured in said recesses in opposed ends of the roller neck and the inner races being secured to said arbor, each of the bosses having an annular groove on its end adjacent the roller neck adapted to receive a portion of the outer race of said bearing, said annular groove defining an annular projection, said annular projection being adapted to engage the outer edge of the corresponding inner race of the anti-friction bearing to thus cause the proximate ends of the axially spaced bosses to be disposed in closely spaced relation to the adjacent ends of the roller neck and whereby the bosses and the arbor may rotate freely relative to the roller neck and vice versa.
